UNITED STATES PATENT OFFICE.

JOHN GOOD, OF GARDEN CITY, NEW YORK, ASSIGNOR TO GOOD INVENTIONS CO., OF BROOKLYN, NEW YORK, A CORPORATION OF NEW YORK.

COMBUSTION-ENGINE.

1,376,527.

Specification of Letters Patent.

Patented May 3, 1921.

Continuation of application Serial No. 822,813, filed March 6, 1914. This application filed May 20, 1916, Serial No. 98,734. Renewed July 22, 1920. Serial No. 398,286.

To all whom it may concern:

Be it known that I, JOHN GOOD, a citizen of the United States, a resident of Garden City, Nassau county, New York, have invented the following described Improvements in Combustion-Engines.

The improvements relate to the starting of internal combustion engines particularly of the carburetor type as used in automobiles, 10 motor boats, etc., and the object is to reduce the work required to be done to set such engines at work on their normal cycle, particularly when the fuel is relatively non-inflammable, like kerosene, or in cold weather, or 15 both, this application being a continuation of my prior application, now Patent #1,207,897. The invention comprehends the combination of an engine of the kind referred to, a starting agency therefor (hand 20 crank or starting motor) and a burner constructed to burn with a continuous flame and so organized with said starting agency that, when the various parts are otherwise in proper adjustment or position, the operation 25 of said agency automatically establishes combustion of some of the engine fuel to produce an immediate initial vaporization of the fuel mixture supplied by the carburetor, so that the mere act of turning the 30 engine over once, or a very few turns, is all that is required to start it running under any circumstances of fuel or temperature condition, thereby avoiding the need of a special starting fuel, and the need of priming 35 the engine as well as the prolonged use of the starting agency.

In the accompanying drawings forming part hereof,

Figure 1 represents in side elevation an 40 automobile engine equipped with one form of this invention;

Fig. 2 is a plan of the several parts constituting the heating device and the part heated, on a larger scale;

Fig. 3 is a still larger view in elevation and partly in section, of the parts forming the flame-confining casing of the heating device;

Fig. 4 is a section on the line IV—IV, 50 Fig. 3;

Fig. 5 is a section illustrating the said vaporizing member; and

Fig. 6 is a cross-section on line VI—VI thereof.

Referring to Fig. 1, the parts of the automobile engine therein shown comprise the cylinders 1, the crank casing 2, the water connections 3, radiator 4, crank shaft 5, flywheel 6, and a starting device 7.

The engine illustrated is assumed to be 60 one adapted for burning kerosene or other heavy liquid fuel requiring heat for its vaporization, for which purpose the vaporizer, or some part of the engine, is normally kept heated by the combustion in the engine 65 or engine exhaust gases, which latter in the case illustrated are taken from the exhaust manifold 8 by a pipe 9, and passed through the vaporizer or part 10 to be heated and thence to an exhaust pipe 11 leading to a 70 muffler or other safe exhaust outlet 12. Part or all of the exhaust gases may thus be utilized as the source of heat, according to requirements, the excess gases being by-passed direct to the exhaust by the appropriate adjustment of the valves 13 through a by-pass pipe 14. The parts marked 15 and 16 are 75 the means for introducing the fuel and air to the vaporizer, but the particular construction of these parts, and of the vaporizer, is 80 of no consequence to the present invention and need not be described, being the subject of a separate application filed April 9, 1914, Serial No. 830705. The vaporized mixture enters the manifold 17 and thence passes into 85 the several cylinders of the engine, as will be evident. A thermostat 18 is shown in the connections between the vaporizer and the manifold 17 to operate the by-pass valves 13, through its bell-crank and link connections 90 19, so that only such portion of the exhaust gases will traverse the vaporizer as may be necessary for its operation or to maintain a substantially uniform temperature in the 95 vaporized mixture.

In order to start such an engine, or any engine using heavy fuel oil which is vaporized by the heat of the engine's combustion process, its vaporizing agencies must be first heated until the engine is able to generate 100 sufficient heat, by its exhaust or otherwise to assume its regular operation. For this purpose a flame or blast of hot combustion gases is provided which encounters the part to be heated, and in the present case passes 105 through a part of the path normally taken by the exhaust gases, discharging into the exhaust 12. The combustion is produced au-

tomatically as by the operation of a crank such as the crank 7, or by any source of mechanical power, as later explained, and is confined in such manner that no flame can escape where it might ignite or injure adjacent material. The flame can be admitted to the normal path of the exhaust gases at any point in the latter, either close to the cylinder heads or close to the vaporizer, as preferred, and in the present case it enters close to the vaporizer through the fitting 20, which accommodates the by-pass valves 13 above referred to. This fitting is provided with a branch passage 21 inclined toward the heater of the vaporizer and provided with a shut-off valve 22, which can be closed when necessary for the purpose of isolating the burner from the engine exhaust.

The burner or flame-generating part of the heating device is formed of two united parts 23 and 24, connected to the inclined branch pipe 21 of the fitting in such manner as to give the flame an easy entrance to the latter, and the said parts together with the vaporizer 10 and exhaust pipe 11 form the casing or passage of the heating device in which the flame is confined. The part to be heated is thus incorporated in or within the casing of the device. The burner chamber is equipped with a liquid fuel nozzle 25, in the part 24, adapted to take liquid fuel from a float chamber 26, the latter being supplied through a pipe 27, from the fuel supply pipe 15. As will be plain without description, the fuel oil or liquid is kept at a constant level in this chamber by the float controlled admission valve therein, and the same fuel oil supply pipe supplies this chamber as supplies the engine proper. The same heavy fuel serves the heater as well as the engine. A nozzle 28 enters the end of the burner chamber substantially axially thereof and in aspirating relation to the oil nozzle 25, and is supplied with air under pressure from a positive blower 29. The pipe 30, connecting the air nozzle with the blower, is provided with an air dome 31, so that the air jet from the nozzle 25, will have substantially constant velocity. The air-atomized fuel spray produced by the operation of the two nozzles is intercepted by the two opposing electrodes 32 of an electric igniter 33, which may be of a common type, but is here shown as formed by two separate but similar insulated plugs, mounted close to the nozzles in the casing part 24 and connected with the terminals of a magneto generator 34.

A spark between the electrodes ignites the oil spray without initial or preliminary heating thereof, due to the fineness of the atomization and the relation of the spark thereto, and air or supplemental air is supplied to the resulting flame to support com-

bustion, but at a point slightly in front of the igniting point so that it does not too greatly dilute the spray, which would prevent ignition by the igniter or result in explosions. The supplemental air is supplied, for example, through the annular admission chamber formed by the casing part 23, into which the air is delivered by the pipe 35, from a fan blower 36, and it will be noted that the location of said chamber provides a short space between itself and the spray-projecting means sufficient to accommodate the igniter plug or plugs, the electrodes of which are thus located in an undiluted part of the spray. The blower 36, which may be any type of air compressor, supplies the said supplemental air, unheated, and at a considerably lower pressure than the compressor 29, and the volume so supplied is sufficient to establish substantially complete combustion of the aspirated liquid fuel within the casing and controls the length of the flame, within limits. Inasmuch as the fluid to aspirate the liquid fuel, as well as that for combustion, is derived from sources of higher pressure than atmosphere, it is evident that the interior of the flame casing is under pressure when the device is in operation, so that the burning gases therein are caused to flow with considerable velocity toward the outlet thereof. I have found that high velocity of said gases is desirable for quickly attaining satisfactory temperature, and this condition is promoted by the elongated, or relatively narrow shape of the flame-passage as well as by the air pressure and the open outlet through the engine exhaust.

The plug 37 in the nozzle part of the burner casing is for the purpose of cleaning the oil nozzle 25 when necessary.

The magneto 34 and the air nozzle blower 29 and also the additional air blower 36, are all arranged to be driven simultaneously so that immediately upon the establishment of the proper spray the igniter 33 will ignite it. The operation of the magneto generator may be intermittent or continuous, as desired, but the first spark ordinarily ignites the spray and the continued operation may serve no other purpose than to insure ignition under any circumstances. As a precaution against failure to ignite the electrodes 32 are formed with parts depending below the spark gap so that the fuel liquid collecting by impingement thereon will drain away from the gap and avoid a possible short-circuit of the electrodes by a drop of the liquid bridging the gap.

The simultaneous operation of the nozzles and igniter is effected by connecting the operating shafts of one or both blowers and the armature shaft of the magneto generator all in a single operating system or gear train such as represented for instance by the gears 130

38, 39 and 40, the several speed ratios of which are of course suited for the production of the results desired. The gear 40 is driven by a ratchet clutch pinion 41, meshing with a long pinion 42, the latter meshing with a spur gear 43 driven by the member 7 or whatever device is used for starting the engine in motion. Assuming that device to be a hand crank as indicated, it is 10 first rotated in its full line position (Fig. 2) thereby simultaneously operating the parts above described and generating a flame which warms the vaporizing apparatus to a sufficient extent to form a combustible gas- 15 eous mixture of air and the fuel used in the engine. The flywheel 45 on the shaft 44 of the fan blower assists in this operation. The crank and gear 43 are then pushed inward until the clutch member 46 on the hub of 20 the latter engages with the corresponding clutch member of the crank-shaft 5 and rotates the latter, whereby the engine draws in the vaporized fuel and proceeds on its normal process. As the engine takes up its 25 own motion the clutch 46 will disengage, but the flywheel 45 will still continue the operation of the heater, the ratchet teeth slipping on the pinion 41, until the exhaust from the first few charges has reached the vaporizer, 30 the continued normal operation of the latter being thereafter assured.

While for convenience of illustration I have shown a simple hand-crank 7 as the means for starting the preheater and the 35 engine, it is to be understood that it is used in illustration of any starting device, whether it be the motor generator of a so-called electric self-starter, as used in automobiles and boats, or other means for initially rotating 40 the engine crank-shaft, and if such starting device is an electric motor it will be evident that the current which operates it may likewise serve to operate the igniter 33 without the aid of a magneto 34 as shown in the 45 drawings. With hand-started engines it is of course an advantage to be able to actuate the operating system of the heater at first independently of the engine, engaging later therewith when the parts have reached the 50 working temperature, and this is permitted by the clutch 46 and sliding gear 43 operated as above described.

In Figs. 5 and 6 I have illustrated a metallic vaporizing member 50, in the shape of 55 a star, disposed at the center of the tangential inlet chamber and in the path of the spray. This member serves to distribute the incoming combustion-supporting air and also to vaporize the fuel, and improves the 60 efficiency of the apparatus and is for that reason preferred, although other forms of member may be used for the same purpose.

It will be observed that the particular 65 heating device above described is extremely compact and easily adapted to the engine,

that it ignites the fuel cold and quickly gives high temperature by reason of the high velocity and forced introduction of the fuel, but this invention comprehends any type of burner suitable for the purpose and 70 operated by the engine-starting power as set forth in the claims below. The exhaust pipe 11 in conjunction with the muffler 12 are sufficiently removed from the source of flame to prevent all danger of injury to surrounding parts of an automobile or boat. Should a premature explosion of the atomized spray, or a back-fire, occur for any reason, no escape of flame from the heating 75 device is possible because of the absence of any opening in the casing to serve as an outlet, except of course the normal safe exhaust. Moreover, the blower 29 forms no passage through it for flame, nor does the fan blower 36, but its intake 48 may, if desired, be ex- 80 tended downwardly below the drip pan 49. This source of air pressure might also be a pump or geared blower, if desired.

It will be understood by those skilled in the art that the apparatus above described is 90 not limited in respect of the size or proportion of its parts, nor to the details of their mechanical assemblage or construction, nor to the character of the part to be heated or the manner in which it is constructed or in- 95 incorporated in the casing of the heater and that various omissions, substitutions and alterations in the form and operation of the device may be made without departing from the invention.

100 I claim:

1. The combination in an automobile type internal combustion engine, of a carbureter, a liquid fuel burner containing a spark plug and air and fuel admission means arranged 105 to establish and maintain a continuous flame, and a starting agency for rotating the engine, said parts being severally adapted and mutually organized to automatically supply heated charge mixture to the engine cylinders by the sole effect of the operation of said starting agency.

2. The combination in an automobile type internal combustion engine, of a carbureter to supply charge mixture to the engine cylinders, a liquid fuel burner incorporating an electric igniter and means for producing continuous flame, means for conducting said flame or its products into heat-transferring 115 relation to said mixture and a starting agency, all said parts being organized for performing their several functions by the sole effect of the operation of said starting agency.

3. The combination in an internal com- 125 bustion engine, of a carbureter to supply charge mixture to the engine cylinders, a heat-transfer mechanism whereby said mixture is normally vaporized by heat developed by the engine's combustion, a liquid 130

- fuel burner incorporating an igniter and means for producing continuous flame, said flame or its products being also arranged to heat the charge mixture, an electric circuit 5 for the igniter and an engine starting agency, the operation of which automatically sets the burner and carburetor in operation to supply the engine with vaporized charge mixture.
- 10 4. In an internal combustion engine, the combination of a combustion means operating independently of the combustion in the engine cylinder and adapted for heating the engine and a double function device 15 for starting the engine, one function thereof being to operate said combustion means without rotating the engine and the other to rotate the engine.
5. The combination with an internal combustion engine, of a starting device therefor, means operating by combustion within itself and independent of the fuel supply to the engine for pre-heating the latter and means whereby the motion of said starting device 25 operates said combustion means.
6. In an internal combustion engine, a pre-heater therefor operating by combustion independent of the combustion in the engine and a starting device for rotating the engine 30 mechanically connected to operate said pre-heater.
7. In an internal combustion engine, a pre-heater therefor comprising an inclosed, forced draft flame passage in heat-transfer 35 ring relation to an element of the engine, a closed burner head adapted to deliver liquid fuel and air into said passage and containing an electric igniter, air compressor and electric apparatus connected to said 40 burner-head and a starting device for the engine adapted to operate the said apparatus.
8. The combination with an internal combustion engine and combustion means for 45 pre-heating the same, of an engine rotating device having connections for operating said combustion means independently of and conjointly with the rotation of the engine.
- 50 9. The combination with an internal combustion engine, mechanically operated combustion means adapted for heating the same until warm enough to perform its nor-
- mal cycle, a starting device for rotating the engine when so warmed, connections where- 55 by said device operates said combustion means and means whereby the said combustion means continues in operation after the engine has started its cycle.
10. The combination with an internal 60 combustion engine, including means for delivering fuel and burning the same therein, of mechanically operated combustion means for heating the engine until warm enough to start it in action, an igniter for said means, 65 means for cranking the engine to start it in action, a single source of energy for operating both said last mentioned means and means for continuing the operation of said combustion means while the engine is in 70 action.
11. The combination in an internal com- 75 bustion engine of a mechanically operated combustion means operating independently of the power combustion in the engine and adapted to heat the same and including air compressor mechanism, electric ignition mechanism and an operating hand crank therefor whereby the engine may be heated by rotating the crank. 80
12. Mechanically operated combustion means comprising an inclosed flame space, liquid fuel-supply and air-compressor mechanism, an electric ignition mechanism and gearing connecting both of said mechanisms 85 including a hand crank the operation where- of produces ignition in a cold state and non-explosive combustion of the fuel in said space.
13. The combination with an internal 90 combustion engine of a liquid fuel burner applied to the engine for heating the same, and a single means for operating said burner and cranking the engine to start it in action.
14. The combination of an internal com- 95 bustion engine having a carburetor connected to supply charge mixture for combustion in the engine cylinder, an inclosed, automatically igniting, liquid fuel burner applied to the engine for heating said mix- 100 ture, and a single means for coincidentally cranking the engine and operating said burner.

In testimony whereof, I have signed this specification.

JOHN GOOD.
